RAILWAY TRACK CIRCUIT APPARATUS

Robert M. Gilson, Pittsburgh, Pa., assignor to
 The Union Switch & Signal Company, Swiss-
 vale, Pa., a corporation of Pennsylvania

Application November 29, 1939, Serial No. 306,705

7 Claims. (Cl. 246—34)

My invention relates to railway track circuit apparatus, and particularly to apparatus for track circuits using coded current.

Railway track circuits have been proposed which use time spaced impulses of direct current with the individual impulses of relatively high peak voltage and of short duration as compared with the duration between successive impulses. The high peak voltage serves as an aid to the shunting sensitivity of the track circuit and the short duration serves to limit the output of the current source to a relatively low energy level. In such track circuits code following track relays are provided for controlling the signaling circuits. It has been found that when adverse train shunting conditions prevail due to rusty rail surfaces, light-weight high-speed trains or other operating conditions, a few impulses of current of sufficient magnitude to operate the track relay may reach the relay now and then past a poor train shunt with the result an undesirable proceed signal indication may be established for an interval.

Accordingly, a main object of my invention is the provision of novel and improved apparatus for use with track circuits supplied with coded current wherewith an undesirable proceed signal indication due to adverse train shunting conditions is avoided. The above object together with other advantages of my invention I accomplish by the provision of a chain of relays which are sequentially picked up by consecutive operations of the code following track relay and the last one of which chain of relays must be picked up before a proceed signal is displayed. Consequently a number of successive impulses of the track circuit current predetermined according to the number of relays provided in the chain of relays must operate the code following track relay before the proceed signal circuit is closed. The loss of a single one of the successive impulses of the track circuit current drops all of the relays already operated thus necessitating a new start in the counting of the current impulses. In other words, the chain of relays governed by the code following track relay in accordance with my invention causes the display of a stop signal even when the train shunt is effective only intermittently while a train occupies the track circuit, and a false proceed signal due to a loss of train shunt is avoided unless such loss of train shunt persists for more than the number of current impulses necessary to make a complete count of the chain of relays.

I shall describe one form of apparatus em-

bodying my invention, and shall then point out the novel features thereof in claims.

In the accompanying drawing which is a preferred form of apparatus embodying my invention, the reference characters 1a and 1b designate the track rails of a stretch of railway over which traffic normally moves in the direction indicated by an arrow and which rails are formed by the usual insulated rail joints 2 into a track section W—X which section may be one of a series of consecutive sections of a signal system. The section W—X is provided with a track circuit comprising a source of coded direct current connected across the rails at one end of the section and a code following track relay connected across the rails at the other end of the section.

The source of coded direct current for the track circuit of section W—X includes a battery 5, a code transmitter CT and a track transformer WT. As here shown the secondary winding 6 of transformer WT is connected across the rails adjacent the exit end of section W—X over wires 7 and 8, a current limiting resistor 9 being preferably interposed in wire 8. The primary winding 10 of transformer WT is connected with battery 5 over a contact member 11 of the code transmitter CT. A condenser 12 is preferably connected across primary winding 10 to improve the operation. The code transmitter CT may take the form of any one of several well-known structures for such devices and it is sufficient to point out that as long as the operating winding 13 of code transmitter CT is supplied with current from a source whose terminals are indicated at B and C, the contact member 11 is operated at a preselected code rate, such as, for example, 75 operations per minute. The contact member 11 is biased to normally engage a contact 14 and is operated to break engagement therewith once each operation of the code transmitter. When contact 11—14 is closed current flows from battery 5 to primary winding 10 and magnetic energy is stored in the magnetic circuit of the transformer WT. The circuit including battery 5 and primary winding 10 is so proportioned as to its time constant that the magnetic energy builds up relatively slow and little if any electromotive force is induced in secondary winding 6. At least the electromotive force induced in secondary winding 6 when energy builds up in transformer WT is so small in magnitude it can be neglected. When contact member 11 of code transmitter CT breaks engagement with contact 14, the flow of current from battery 5 is interrupted and the magnetic energy stored in trans-

former WT decays rapidly so that an electro-motive force of relatively large magnitude is induced in secondary winding 6 and a current impulse of relatively high peak voltage is supplied to the track circuit of section W—X. This impulse of current is of a given polarity and of short duration, at least the duration of the current impulse is short as compared with the duration between successive current impulses when 10 the code rate of 75 impulses per minute is used. It follows that as long as code transmitter CT is operated current impulses of the preselected code rate of 75 impulses per minute are supplied to the track circuit of section W—X.

15 It will be understood, of course, that I do not limit my invention to coded current having 75 impulses per minute or to impulses of relatively high peak voltage and short duration but such code rate and characteristics have been found 20 satisfactory.

The track circuit of section W—X is provided with a code following track relay CF. The code following relay CF may be any one of several well-known types and in the instant case relay 25 CF is a neutral relay whose operating winding 15 is connected across the rails adjacent the entrance end of section W—X over wires 16 and 17. Relay CF is provided with two contact members 18 and 19 which are biased to engage back 30 contacts 20 and 21, respectively, and are raised to engage respective front contacts 22 and 23 when the relay is energized. Relay CF is effectively energized to operate its contact members 18 and 19 by each individual current impulse 35 supplied to the track circuit by the apparatus at the exit end of section W—X. Consequently, contact members 18 and 19 are operated at the code rate preselected for the track circuit, and in this case are operated at the rate 40 of 75 times per minute when the section W—X is unoccupied, but both contact members 18 and 19 are inactive in engagement with their respective back contacts 20 and 21 when the section 45 is occupied by a train such as indicated at TV in the drawing.

The code following track relay CF has associated therewith a chain of relays consisting of two control relays FSA and BSA, two repeater relays XI and X2, and four counting relays C1, 50 C2, C3 and C4.

The control relays FSA and BSA are slow releasing in character, their release periods being sufficient to bridge from one impulse to the next of the track circuit current but insufficient to 55 bridge two such impulses. The repeater relays XI and X2 and the counting relays C1, C2, C3 and C4 are each of the usual acting type.

The control relays FSA and BSA and the counting relay C4 control the operating circuits of a 60 wayside signal S1 which governs traffic through the section W—X. Signal S1 may be any of the standard types and as here shown is a color light signal provided with two lamps G and R for displaying a proceed and a stop signal indication, 65 respectively.

It is believed that the circuits governed by the code following track relay CF for operating the associated chain of relays can best be understood by a description of their operation through the 70 steps necessary before a proceed signal indication for signal S1 is effected. At the start it will be assumed that section W—X is occupied by the train TV so that the code following track relay CF is inactive and all of the other relays are 75 released as shown in the drawing. With control

relay FSA released closing back contact 68 a simple circuit easily traced is closed for illuminating the lamp R of signal S1 causing that signal to display its stop indication. It is also to be observed that when relay FSA is picked up 5 closing front contact 65 and relay BSA is released closing back contact 69, a second circuit is completed for illuminating lamp R of signal S1. Furthermore when both control relays FSA and BSA are picked up closing front contacts 65 and 10 66, respectively, and the last relay C4 of the chain of relays is released closing back contact 70, a third circuit is formed for lamp R of signal S1. Hence, the lamp R of signal S1 is illuminated and a stop signal displayed by signal S1 until both 15 control relays FSA and BSA, and the last relay C4 of the chain of relays are picked up. To bring about such operation of the control relays FSA and BSA and the last relay C4 of the chain of relays requires ten operation steps.

Assuming the train TV which occupies section W—X moves out of the section, the first current impulse supplied to the track circuit after the train vacates the section initiates the first operation step. On the first operation step code following track relay CF is picked up closing front contact 18—22 so that current flows from the terminal B of the current source over front contact 18—22, wire 24, back contacts 25, 26, 27, 28, 29, 30 and 31 of relays C4, C3, C2, C1, X2, 30 XI and BSA, respectively, winding of relay FSA and to terminal C of the current source, and relay FSA is picked up. Since control relay FSA is slow releasing in character it is thereafter energized and held picked up over its stick circuit 35 including front contact 18—22 of relay CF and its own front contact 72 as long as the track relay CF is operated by each successive impulse of the track circuit current. If track relay CF is not operated by any one of the impulses of the 40 track circuit current, the control relay FSA is released because its slow release period is not sufficient to bridge the interval of two impulses of the track circuit current. Furthermore, if control relay FSA is once released, it cannot be reenergized except over its pick-up circuit which includes the back contacts 25 to 31, inclusive, of the several associated relays.

The second operation step is initiated when the first impulse of track circuit current ceases 50 and track relay CF is released to close back contact 18—20. Current now flows from terminal B of the current source over back contact 18—20 of relay CF, front contact 32 of relay FSA, winding of relay BSA and to terminal C, and relay 55 BSA is picked up. Since control relay BSA is slow releasing in character it is retained energized as long as track relay CF is operated at the pre-selected code rate and the control relay FSA is picked up closing front contact 32.

The third operation step is initiated when a second impulse of current is supplied to the track circuit to pick up the track relay CF. Current now flows from terminal B over front contacts 33 and 34 of relays BSA and FSA, respectively, front contact 19—23 of relay CF, wire 35, back contacts 36, 37, 38 and 39 of relays C4, C3, C2 and C1, respectively, winding of relay XI and to terminal C, and relay XI is picked up after which it is held picked up over a stick circuit involving terminal B, front contacts 33 and 34, wire 57, back contact 40 of relay X2, front contact 41 and winding of relay XI, and terminal C.

The fourth operation step is started when the second impulse of track circuit current ceases 75

causing track relay CF to be released. Current now flows from terminal B over front contacts 33 and 34 of relays BSA and FSA, respectively, back contact 19-21 of relay CF, front contact 42 of relay X1, back contact 43 of relay X2, wire 44, back contacts 45 and 46 of the even numbered relays C4 and C2 of the counting relays, winding of relay C1 and to terminal C, and relay C1 is picked up. Relay C1 is then retained energized over a stick circuit including terminal B, front contacts 33 and 34, wire 57, front contact 41 and winding of relay C1 and terminal C as long as the two control relays FSA and BSA are picked up closing front contacts 34 and 33.

The fifth operation step is effected when the third impulse of current is supplied to the track circuit to pick up the track relay CF and current flows from terminal B over front contacts 33 and 34 of relays BSA and FSA, respectively, front contact 19-23 of relay CF, wire 35, back contacts 36, 37 and 38 of relays C4, C3 and C2, respectively, front contact 49 of relay C1, winding of relay X2 and to terminal C, and relay X2 is picked up opening at its back contact 40 the stick circuit for repeater relay X1 so that relay X1 is immediately released. Repeater relay X2 is then retained energized over a stick circuit involving terminal B, front contacts 33 and 34, wire 57, back contact 50 of relay X1, front contact 51 and winding of relay X2 and terminal C.

The sixth operation step is effected when the third impulse of track circuit current ceases so that relay CF is released and current flows from terminal B over front contacts 33 and 34 of relays BSA and FSA, respectively, back contact 19-21 of relay CF, back contact 52 of relay X1, front contact 53 of relay X2, wire 54, back contact 55 of relay C3, front contact 56 of relay C1, winding of relay C2 and to terminal C, and relay C2 is picked up. Relay C2 is then retained energized over a stick circuit which is the same as the stick circuit traced for relay C1 up to wire 57, thence over front contact 58 and winding of relay C2 to terminal C.

The seventh operation step is effected when the fourth impulse of current is supplied to the track circuit causing track relay CF to be picked up and current flows from terminal B over front contacts 33 and 34 of relays BSA and FSA, respectively, front contact 19-23 of relay CF, wire 35, back contacts 36 and 37 of relays C4 and C3, respectively, front contact 59 of relay C2, winding of repeater relay X1 and to terminal C, and relay X1 is then picked up to open at its back contact 50 the stick circuit for relay X2 so that repeater relay X2 is immediately released closing back contact 40. Repeater relay X1 is then retained energized over its previously traced stick circuit.

For the eighth operation step the fourth impulse of track circuit current ceases so that the track relay CF is released and current flows from terminal B over front contacts 33 and 34 of relays BSA and FSA, respectively, back contact 19-21 of relay CF, front contact 42 of relay X1, back contact 43 of relay X2, wire 44, back contact 45 of relay C4, front contact 60 of relay C2, winding of relay C3 and to terminal C, and relay C3 is picked up. Relay C3 is then retained energized over a stick circuit which is the same as traced for relay C1 up to wire 57 and thence over front contact 61 and winding of relay C3 to terminal C.

The ninth operation step is effected when the fifth impulse of current is supplied to the track circuit causing track relay CF to be picked up so that current flows from terminal B over front

contacts 33 and 34 of relays BSA and FSA, respectively, front contact 19-23 of relay CF, wire 35, back contact 36 of relay C4, front contact 62 of relay C3, winding of repeater relay X2 and to terminal C, and relay X2 is again picked up opening at its back contact 40 the stick circuit for repeater relay X1 with the result that relay X1 is immediately released closing back contact 53 and relay X2 is retained energized over its previously traced stick circuit.

For the tenth operation step the fifth impulse of track circuit current ceases so that track relay CF is released and current flows from terminal B over front contacts 33 and 34 of relays BSA and FSA, respectively, back contact 19-21 of relay CF, back contact 52 of relay X1, front contact 53 of relay X2, wire 54, front contact 63 of relay C3, winding of relay C4 and to terminal C, and relay C4 is picked up after which it is retained energized over a stick circuit which is the same as traced for relay C1 up to wire 57 and thence over front contact 64 and winding of relay C4 to terminal C.

With the last relay C4 of the chain of relays picked up opening back contact 70, the circuit for lamp R of signal S1 is opened and the lamp is dark. A proceed signal circuit can now be traced from terminal B over front contacts 65, 66 and 67 of relays FSA, BSA and C4, respectively, lamp G of signal S1 and to terminal C, and the lamp G is illuminated so that signal S1 displays a proceed signal.

It is to be observed that on the next impulse of track circuit current and relay CF is picked up closing front contact 19-23 a circuit is completed from terminal B over front contacts 33 and 34 of relays BSA and FSA, respectively, front contact 19-23 of relay CF, wire 35, front contact 71 of relay C4, winding of repeater relay X1 and to terminal C, and relay X1 is picked up to open at its back contact 50 the stick circuit for repeater relay X2 so that relay X2 is released closing back contact 40 and relay X1 is retained energized over its stick circuit. From this point on relay X1 is retained energized over its stick circuit so that the repeater relays X1 and X2 are not further operated, relay X1 being picked up and relay X2 being released.

Assuming train TV occupies section W-X and because of a poor train shunt and say, for example, three successive impulses of track circuit current of sufficient magnitude to operate the track relay CF get past the poor train shunt but the fourth impulse of current is insufficient to operate relay CF, the above described operation is effected up to and including the sixth operation step so that relays FSA, BSA, X2, C1 and C2 of the chain of relays are picked up. At the seventh operation step, however, relay FSA is released opening front contacts 32 and 34 because track relay CF is not picked up. The opening of front contact 32 deenergizes relay BSA to release that relay, and the opening of front contact 34 opens the stick circuits for relays X2, C1 and C2 and these relays are released with the result that all of the relays are reset at their released positions and the operation must be started all over again. Consequently, a proceed signal is not effected unless the poor train shunt persists for at least five impulses of the track circuit current.

It is apparent that the chain of relays can include additional counting relays controlled over circuits similar to those provided for relays C1 to C4, inclusive, and a number greater than five im-

pulses is required before the proceed signal is displayed. Also the chain of relays can include less than four counting relays if desired and a less number of track circuit impulses required before

5 the proceed signal is effected.

Although my invention has been disclosed when used with a track circuit supplied with coded direct current, it is apparent it can be used with a track circuit supplied with coded alternating

10 current.

15 Although I have herein shown and described only one form of railway track circuit apparatus embodying my invention, it is understood that various changes and modifications may be made therein within the scope of the appended claims without departing from the spirit and scope of my invention.

Having thus described my invention, what I claim is:

20 1. Track circuit apparatus for use with a track circuit supplied with time spaced impulses of current for operating a code following track relay comprising, a first and a second control relay each provided with a slow release period sufficient only to bridge from one impulse to the next of such track circuit current, means including a front contact of said code following track relay to energize said first control relay, means including a front contact of said first control relay and a back contact of said code following track relay to energize said second control relay, a preselected number of counting relays, circuit means including a front contact of each of said control relays and a back contact of said code following track relay to sequentially energize said counting relays in response to operation of the code following track relay, a stick circuit for each of said counting relays each of which stick circuits includes a front contact of each of said control relays to retain the counting relays picked up to count by the number of said counting relays picked up the successive current impulses of the track circuit until all of the relays of said counting relays are picked up, and a signal circuit including a front contact of the last relay of said counting relays.

25 2. Track circuit apparatus for use with a track circuit supplied with time spaced impulses of current for operating a code following track relay comprising, a control relay having a slow release period sufficient only to bridge from one impulse to the next of such track circuit current, means including a front contact of said code following track relay to energize said control relay, a first and a second repeater relay, means including a front contact of said control relay and a front contact of said code following track relay to alternately energize said first and second repeater relays in response to operation of the code following track relay, a preselected number of counting relays; a first circuit including a front contact of said control relay, a back contact of said code following track relay and a front contact of said first repeater relay to sequentially energize the odd numbered relays of said counting relays; a second circuit including a front contact of said control relay, a back contact of said code following track relay and a front contact of said second repeater relay to sequentially energize the even numbered relays of said counting relays; a stick circuit for each of said counting relays each of which stick circuits includes a front contact of said control relay to retain the counting relays picked up to count by the number of counting relays picked up the number of

successive current impulses of the track circuit until all of said counting relays are picked up, and a signal circuit including a front contact of the last relay of said counting relays.

3. Track circuit apparatus for use with a track circuit supplied with time spaced impulses of current for operating a code following track relay comprising, a first and a second control relay each provided with a slow release period sufficient only to bridge from one impulse to the next of such track circuit current, means including a front contact of said code following track relay to energize said first control relay, means including a front contact of said first control relay and a back contact of said code following track relay to energize said second control relay, a preselected number of counting relays, circuit means including a front contact of each of said control relays and a back contact of said code following track relay to sequentially energize said counting relays in response to operation of the code following track relay, a stick circuit for each of said counting relays each of which stick circuits includes a front contact of each of said control relays to retain the counting relays picked up to count by the number of said counting relays picked up the successive current impulses of the track circuit until all of the relays of said counting relays are picked up, a first signal circuit including either a back contact of the first control relay or in series a front contact of the first control relay and a back contact of the second control relay or in series a front contact of each of said control relays and a back contact of the last relay of said counting relays, and a second signal circuit including in series a front contact of each of said control relays and a front contact of the last relay of said counting relays.

4. Track circuit apparatus for use with a track circuit supplied with time spaced impulses of current for operating a code following track relay comprising, a first and a second control relay each provided with a slow release period sufficient only to bridge from one such track circuit current impulse to the next, means including a front contact of the code following track relay to energize said first control relay, means including a back contact of the code following track relay and a front contact of the first control relay to energize said second control relay, a first and a second repeater relay, circuit means including a front contact of each of said control relays and a front contact of said code following track relay to alternately energize said repeater relays in response to operation of the code following track relay, a preselected number of counting relays, a circuit including a back contact of said code following track relay and a front contact of said first repeater relay to energize the odd numbered relays of said counting relays one at a time, another circuit including a back contact of said code following track relay and a front contact of said second repeater relay to energize the even numbered relays of said counting relays one at a time, a stick circuit for each of said counting relays each of which stick circuits includes a front contact of each of said control relays, and a signal circuit including a front contact of the last relay of said counting relays.

5. Track circuit apparatus for use with a track circuit supplied with time spaced impulses of current for operating a code following track relay comprising, a control relay having a slow release period sufficient only to bridge from one impulse to the next of such track circuit current, means

including a front contact of said code following track relay to energize said control relay, a first and a second repeater relay, means including a front contact of said control relay and a front contact of said code following track relay to energize the first repeater relay and release the second repeater relay in response to the even numbered impulses of the track circuit current and to energize the second repeater relay and release the first repeater relay in response to the odd numbered impulses of the track circuit current after the first impulse, a preselected number of counting relays; a first circuit including a back contact of said code following track relay, a front contact of said first repeater relay and a back contact of said second repeater relay to energize the odd numbered relays of said counting relays one at a time; another circuit including a back contact of said code following track relay, a back contact of said first repeater relay and a front contact of said second repeater relay to energize the even numbered relays of said counting relays one at a time, a stick circuit for each of said counting relays each of which stick circuits includes a front contact of said code following track relay and a back contact of said control relay, and a signal circuit including a front contact of the last relay of said counting relays.

6. Track circuit apparatus for use with a track circuit supplied with time spaced impulses of current for operating a code following track relay comprising, a chain of relays including a control relay having a slow release period sufficient to bridge the interval between successive impulses of such track circuit current only and a preselected number of counting relays, a pick-up circuit including a front contact of said code following track relay and a back contact of each of said counting relays to energize said control relay, a stick circuit including a front contact of said code following track relay to retain said control relay picked up when the track relay is operated by each successive impulse of track circuit current, circuit means including a front contact of said control relay and a back contact of said code following track relay to sequentially energize said

counting relays in response to operation of the track relay, a stick circuit for each of said counting relays each of which stick circuits includes a front contact of said control relay to determine by the control relay picked up and number of counting relays picked up the number of successive impulses of track circuit current until all of the chain of relays are picked up, and a signal circuit including a front contact of said control relay and a front contact of the last relay of said counting relays.

7. Track circuit apparatus for use with a track circuit supplied with time spaced impulses of current for operating a code following track relay comprising; a chain of relays consisting of a first and a second control relay each having a slow release period sufficient to bridge the interval between successive impulses of such track circuit current only, a first and a second repeater relay and a preselected number of counting relays; a pick-up circuit including a front contact of said code following track relay and a back contact of each of the remaining relays of said chain of relays to energize said first control relay, a stick circuit including a front contact of said code following track relay to retain said first control relay picked up, means including a front contact of said first control relay and a back contact of said code following track relay to energize said second control relay, means including a front contact of each of said control relays and a front contact of said code following track relay to alternately pick up and release said first and second repeater relays, circuit means including a back contact of said code following track relay and a contact of each of said repeater relays to sequentially energize said counting relays in step with operation of the track relay, a stick circuit for each of said counting relays each of which stick circuits includes a front contact of each of said control relays, and a signal circuit including a front contact of the last relay of said chain of relays.
